Primary Examiner — Derrick E Holland*Assistant Examiner* — Andrew Kerr*(74) Attorney, Agent, or Firm* — Revolution IP, PLLC(57) **CLAIM**

The ornamental design for a hot and cold water dispenser, as shown and described.

DESCRIPTION

FIG. 1 is a perspective view of a hot and cold water dispenser showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 depicts an enlarged detail view of portion 8 shown in FIG. 1; and,

FIG. 9 depicts and enlarged detail view of portion 9 shown in FIG. 1.

The evenly-spaced broken lines in the drawing views depict portions of a hot and cold water dispenser and form no part of the claimed design.

The dot-dash broken lines framing portions of the claimed design that are illustrated in enlargements form no part of the claimed design.
